CATHODE-RAY TUBE

Richard C. Raymond, State College, Pa., assignor
to the United States of America as represented
by the Secretary of War

Application December 17, 1945, Serial No. 635,587

1 Claim. (Cl. 315—2)

1

The invention relates in general to cathode ray oscilloscopes and in particular to a cathode ray tube having a vacuum tube amplifier incorporated within its envelope.

In the conventional type of oscilloscope, in which a separate amplifier is used, the maximum frequency which can be presented on the screen of the cathode ray tube has a definite upper limit. In most instances, the highest frequency which may be presented is limited, among other things, by the capacitance associated with the plate of the final amplifier tube, the capacitance associated with the deflecting plate of the cathode ray tube and the capacitance of the leads connecting the two plates.

It is an object of this invention to device a cathode ray tube which may be used for the presentation of very high frequencies.

It is a further object of this invention to reduce the distributed capacitance in the circuit between the anode of the vacuum tube amplifier and the deflecting plate of the cathode ray tube.

Other objects and advantages will become readily apparent by referring to the hereinafter described specification.

The tube consists of a conventional cathode ray tube with a vacuum tube amplifier which has one or more grids and in which the vacuum tube anode is also one of the deflecting plates of the cathode ray tube or in which the anode of the vacuum tube amplifier is electrically connected to one of the deflecting plates.

The cathode ray tube of this invention is capable of responding to much higher frequencies than conventional cathode ray tubes since the distributed capacitance, which in most cases limits the upper frequency to which an oscilloscope can respond, has been greatly lowered by including the vacuum tube amplifier within the envelope of the cathode ray tube.

The invention will be best understood by reference to the single figure of the accompanying drawing which shows a simple embodiment of the invention.

The figure shows a cathode ray tube 1 which has conventional deflecting plates 2 and 3 with leads connecting the two deflecting plates to a source of potential. A resistor 4 is included between deflecting plate 3 and the source of potential. A control grid 5 is disposed adjacent to the deflecting plate 3 and the cathode 6 is also included within the envelope in such a manner that the stream of electrons from the cathode 6 to the deflecting plate 3, which serves also

2

as an anode, will be controlled by the bias on the control grid 5.

The above describes a simple embodiment of the invention in which one of the deflecting plates is used as an anode for the vacuum tube amplifier. It is, of course, obvious that the vacuum tube amplifier may have a separate anode directly connected to the deflecting plate of the cathode ray tube by a short direct length of wire. This would, of course, be a more practical form since a tube utilizing merely the deflecting plate of the cathode ray tube would not be a very efficient amplifying device.

In the operation of the device, a signal applied to the control grid 5 will vary the anode current flowing through resistor 4 and will accordingly vary the potential difference between deflecting plates 2 and 3. The amount of deflection of the electron beam in the cathode ray tube depends on the difference in potential between the two deflecting plates. It can be readily seen, therefore, that the amount of deflection of the electron beam can be controlled by the application of a signal to the control grid 5.

The highest frequency to which the device of this invention can respond is greatly increased over conventional arrangements since the distributed capacity of the connection between the vacuum tube amplifier and the deflecting plate can be greatly reduced.

The vacuum tube amplifier is shown in the figure as a triode in which one of the deflecting plates serves as its anode. The figure was drawn in this manner solely for the sake of simplicity and for the purpose of illustration. It is not intended that the invention be limited to the use of a triode since any well known type of tube can be placed within the envelope of the cathode ray tube and have its anode connected to one of the deflecting plates.

It will be apparent that there may be deviations from the invention as described which still fall fairly within the spirit and scope of the invention. For example, if desired, two vacuum tube amplifiers may be located within the envelope of the cathode ray tube in order to provide push-pull amplification for the deflection signal.

Accordingly I claim all such deviations which fall fairly within the spirit and scope of the invention as identified in the hereinafter claim.

What is claimed is:

In a cathode ray oscilloscope, a source of positive potential, a cathode ray tube including an evacuated envelope and a beam forming cathode, a pair of deflecting plates, means for electrically

connecting said deflecting plates to said source of potential, resistor means within said envelope connected between one of said deflecting plates and said source of potential, an amplifier cathode within said envelope, and a control grid within said envelope located between said deflecting plate and said amplifier cathode in such a manner that the flow of current through said resistor means may be controlled by the potential applied to said control grid, the voltage drop developed 10 across said resistor by said current being impressed directly upon said one deflection plate.
